THERMOSTAT

Robert Burkle, North Bergen, N. J., assignor of
one-half to Richard Merrifield, New York,
N. Y.

Application March 14, 1933. Serial No. 660,620

10 Claims. (Cl. 200—138)

This invention relates to new and useful improvements in thermostats particularly intended for use on automatic dish washing and drying machines.

5 This application is a continuation in part of my application entitled Automatic dish washing and drying machines, filed in United States Patent Office on June 4, 1932, Serial No. 615,287.

The invention has for an object the construction of a thermostat which is characterized by a tubular body with a reduced front end and an opened rear end for mounting upon a water or other pipe or object in a manner so that the fluid may enter, a temperature conductive tubular member with a closed rear end mounted at the front through said reduced end of the tubular body and extending towards the rear of the tubular body so as to be surrounded by the fluid, and a thermostatic arrangement mounted within the 15 conductive tubular member. This construction provides for the efficient transfer of temperature from the fluid to the thermostat.

Still further this invention contemplates the novel arrangement of a bimetallic strip and a 20 plain strip disposed parallel to each other and extending through the conductive tubular member and supported at the rear ends upon the closed rear end of the said conductive tubular member in a manner so that the temperature may 25 effect the bimetallic strip and cause it to move towards or away from the plain strip and so cause functioning of the thermostat.

Furthermore as another object of this invention it is proposed to mount insulated terminals 30 upon the free ends of said strips with contacts to make connection in some electric circuit to control the circuit according to the temperature effects upon the bimetal strip, and to arrange a finger upon the free end of the plain strip and 35 to provide a means in conjunction with the finger for moving and holding away the finger at various positions so as to flex the plain strip and move the terminals to predetermined separated 40 space but allowing the plain strip and bimetal strip to continue its movement after contact has 45 been made.

Furthermore the invention contemplates the provision of a casing attached upon the front of 50 the tubular body in manner so as to house the finger mentioned in the previous paragraph and the mechanism for moving and holding this finger except a control knob arranged outside of 55 said casing and mounted upon a stem extending into the casing to lift the plain strip away from

the bimetal strip and adjust the operation of the mechanism.

Still further this invention contemplates a novel arrangement whereby an adjustment is provided for changing the range of operation on 60 the mechanism in moving the finger so as to increase the amplitude of operation of the thermostatic device.

Still further this invention contemplates the construction of a device as mentioned which is 65 simple and durable and which may be manufactured and sold at a reasonable cost.

For further comprehension of the invention, and of the objects and advantages thereof, reference will be had to the following description 70 and accompanying drawing, and to the appended claims in which the various novel features of the invention are more particularly set forth.

In the accompanying drawing forming a material part of this disclosure:—

75

Fig. 1 is a longitudinal sectional view of a thermostat constructed according to this invention.

Fig. 2 is an end elevational view of Fig. 1.

Fig. 3 is a sectional view taken on the line 3—3 80 of Fig. 1.

Fig. 4 is a fragmentary view similar to a portion of Fig. 1 but illustrating a modified construction.

Fig. 5 is a sectional view taken on the line 5—5 85 of Fig. 4.

The thermostatic device according to this invention comprises a tubular body 10 with a reduced front end 11 and an opened rear end 12 for mounting upon a water pipe or the like in a 90 manner so that the fluid may enter. More particularly, the tubular body 10 is shown threaded- 95 ly engaged into a portion of a pipe fitting 13 arranged in the pipe line 14 through which the fluid passes. A conductive tubular member 15 with a closed rear end 16 is mounted at the front through the reduced end 11 and extends towards the rear end of the tubular member so as to be surrounded by the fluid. Upon the rear end of the temperature conductive tubular member, a bimetal strip 17 and a plain metal strip 18 are 100 arranged parallel to each other and extended through said conductive tubular member 15 and supported at the rear ends upon the closed end, that is, upon the plug 16 of the conductive tubular member.

An insulated terminal 19 is mounted upon the free end of the bimetal strip 17 and another insulated terminal 20 is mounted upon the free end 110 of the plain strip 18. These terminals are for

connection in an electric circuit to control the circuit according to certain temperature changing effects upon the bimetal strip. A finger 21 is attached upon the free end of the plain strip 18. 5 This finger engages against the periphery of a cam 22 arranged so as to flex the plain strip to hold the terminals separated to predetermined amounts.

A casing 23 is attached upon the rear end of 10 the tubular body 10 which is provided with an enlargement or flange 24 to accommodate the casing. The casing 23 houses the cam 22, the finger 21 and all parts to the rear of these parts. The front 25 of the casing 23 is formed from 15 transparent material and immediately behind this material there is located an opaque disc 26 which is printed or inscribed with a scale 27 to indicate the temperature at which the thermostatic device will act. A pointer 28 is arranged 20 to travel over the scale 27 and is attached upon a spindle 29 rotatively engaged through the front 25 of the casing and the disc 26. An operating knob 30 is attached upon the outer end of the spindle 29. The inner end of the spindle 29 is 25 attached at the point 31 upon the cam 22 so as to be capable of rotating the cam to cause the finger 21 to move according to the outline or periphery of the cam.

As insulated terminal 19 is mounted upon the 30 free end of the bimetal strip 17 and another insulated terminal 20 is mounted upon the free end of the plain strip 18. These terminals are for connection in an electric circuit to control the circuit according to certain temperature changing 35 effects upon the bimetal strip. A finger 21 is attached upon the free end of the plain strip 18. This finger engages against the periphery of a cam 22 arranged so as to flex the plain strip terminal away and separated to predetermined 40 amounts.

A casing 23 is attached upon the rear end of the tubular body 10 which is provided with an enlargement or flange 24 to accommodate the casing. The casing 23 houses the cam 22, the 45 finger 21 and all parts to the rear of these parts. The front 25 of the casing 23 is formed from transparent material and immediately behind this material there is located an opaque disc 26 which is printed or inscribed with a scale 27 to 50 indicate the temperature at which the thermostatic device will act. A pointer 28 is arranged to travel over the scale 27 and is attached upon a spindle 29 rotatively engaged through the front 25 of the casing and the disc 26. An operating 55 knob 30 is attached upon the outer end of the spindle 29. The inner end of the spindle 29 is attached at the point 31 upon the cam 22 so as to be capable of rotating the cam to cause the finger 21 to move according to the outline or 60 periphery of the cam. This periphery is so designed as to gradually move the finger further away relative to the bimetal strip 17 when turned in one direction and to allow the resiliency of the plain strip 18 to move the finger closer to the bimetal strip 17 when the cam is moved in the other direction.

A cable casing 32 is attached upon the bottom of the casing 23 and is adapted to house the leads 33 which connect with stationary insulated terminals 34 mounted upon the flange 24 from which coiled leads 35 connect with the terminals 19 and 70 20. Stops 36 project from the ends of the cam 22 so as to limit rotation of the cam to positions in which the finger 21 always maintains contact 75 with the periphery thereof.

In Figs. 4 and 5 a modification of the invention has been disclosed in which provision has been made for increasing the operative range of the thermostatic device. This arrangement relates particularly to the cam action for moving the finger 21. The cam comprises a core portion 37 and a peripheral portion 38 which is provided with a rod 39 engaged radially into the core portion 37 so that the peripheral portion may move from a position in intimate contact with the outer surface of the core portion 37 to other positions extended outwards. A resilient means is provided for normally urging the peripheral portion 38 inwards and comprises a spring 40 arranged coaxially upon the rod 39 and disposed within a recess formed in the core portion 37 and acting between one end of the recess and a head 42 formed upon the inner end of the rod 40.

A means is provided for holding the peripheral portion 38 in an extended position when desired to a predetermined amount. This means comprises an arm 43 fixed upon a tube 44 engaged over a stem 45 which connects the core portion 37 with the operating knob 30. The arm 43 is disposed in intimate contact with one side of the core portion 37 and the peripheral portion 38 is wider than the core portion so as to extend outwards over the edge thereof and so be engageable by the arm 43. The tubular member 44 extends from the arm 43 through the disc 26 and the front 105 of the casing 23 to the exterior. A finger 46 is attached upon the extended end of the tube 44 and engages within one or another of a pair of recesses 47 formed upon the periphery of the knob 30. The arrangement is such that in one position 110 of the finger 46 relative to the knob 30 to the arm 43 holds the peripheral portion 38 of the cam extended, while in the second position of the finger 46 with relation to the knob 30 the arm 43 is in an idle position as indicated by the dot and dash 115 lines in Fig. 5 so that the peripheral portion of the cam may move and does move under the action of the spring 40 to its retracted position. The stop fingers 36 are arranged upon the ends of the peripheral portion 38 of the cam. 120

The operation of the device consists merely in adjusting the knob 30 so as to cause rotation of the cam 22 or the cam 37, 38 so as to move the finger 21 to adjusted positions in which the terminals 19 and 20 are separated to predetermined 125 amounts so that the thermostat acts at a certain temperature as indicated by the pointer 28 operating over the scale 27. In the form of the device illustrated in Figs. 4 and 5 an arrangement has been provided whereby the peripheral portion 130 38 of the cam may be adjusted so as to change the range of possible motion of the finger 28 and so increase the range which is possible to set the thermostatic device. In Figs. 4 and 5 the scale, not shown in the drawing, over 135 which the pointer 28 acts must be graduated so as to properly indicate all temperatures at which the device may be set. The pointer 28 is shown mounted upon the tube 44 and the scale over which the pointer works must be graduated to take into consideration the position of the finger 46 in the grooves 47 or a table of conversion 140 must be supplied in conjunction with the scale so as to interpret the true readings from the scale. 145

While I have shown and described the preferred embodiment of my invention, it is to be understood that I do not limit myself to the precise construction herein disclosed and the right is reserved to all changes and modifications com- 150

ing within the scope of the invention as defined in the appended claims.

Having thus described my invention, what I claim as new, and desire to secure by United States Letters Patent is:—

1. A thermostat for an automatic dish washing and drying machine or the like, comprising a tubular body with a reduced front end and opened at the rear end for mounting upon a water or the like pipe line in a manner so that fluid may enter, a temperature conductive tubular member with a closed rear end and mounted at the front through said reduced end and extending towards the rear of said tubular body so as to be surrounded by said fluid, a bimetal strip and a plain strip parallel to each other and extending through said conductive tubular member and supported at the rear ends upon the closed rear end of said conductive tubular member, a contact mounted on an insulated terminal mounted on the free end of each of said strips for connection in an electric circuit to control the circuit according to certain temperature effects upon the bimetal strip, a finger attached upon the free end of said plain strip, and a cam rotatively supported in a manner so that its periphery acts against the finger to hold away the plain strip flexed so that the said terminals are separated according to predetermined amounts. 80
- 15 2. A thermostat for an automatic dish washing and drying machine or the like, comprising a tubular body with a reduced front end and opened at the rear end for mounting upon a water or the like pipe line in a manner so that the fluid may enter, a conductive tubular member with a closed rear end and mounted at the front through said reduced end and extending towards the rear of said tubular body so as to be surrounded by said fluid, a bimetal strip and a plain strip parallel to each other and extending through said conductive tubular member and supported at the rear ends upon the closed rear end of said conductive tubular member, a contact mounted on an insulated terminal mounted on the free end of each of said strips for connection in an electric circuit to control the circuit according to certain temperature effects upon the bimetal strip, a finger attached upon the free end of said plain strip, and a cam rotatively supported in a manner so that its periphery acts against the finger to hold away the plain strip flexed so that the said terminals are separated according to predetermined amounts. 85
- 20 30 3. A thermostat for an automatic dish washing and drying machine or the like, comprising a tubular body with a reduced front end and opened at the rear end for mounting upon a water or the like pipe line in a manner so that the fluid may enter, a conductive tubular member with a closed rear end and mounted at the front through said reduced end and extending towards the rear of said tubular body so as to be surrounded by said fluid, a bimetal strip and a plain strip parallel to each other and extending through said conductive tubular member and supported at the rear ends upon the closed rear end of said conductive tubular member, a contact mounted on an insulated terminal mounted on the free end of each of said strips for connection in an electric circuit to control the circuit according to certain temperature effects upon the bimetal strip, a finger attached upon the free end of said plain strip, and a cam rotatively supported in a manner so that its periphery acts against the finger to hold away the plain strip flexed so that the said terminals are separated according to predetermined amounts. 90
- 25 35 40 45 50 55 60 65 70 75
4. A thermostat for an automatic dish washing and drying machine or the like, comprising a tubular body with a reduced front end and opened at the rear end for mounting upon a water or the like pipe line in a manner so that the fluid may enter, a conductive tubular member with a closed rear end and mounted at the front through said reduced end and extending towards the rear of said tubular body so as to be surrounded by said fluid, a bimetal strip and a plain strip parallel to each other and extending through said conductive tubular member and supported at the rear ends upon the closed rear end of said conductive tubular member, a contact mounted on an insulated terminal mounted on the free end of each of said strips for connection in an electric circuit to control the circuit according to certain temperature effects upon the bimetal strip, a finger attached upon the free end of said plain strip, and a cam rotatively supported in a manner so that its periphery acts against the finger to hold away the plain strip flexed so that the said terminals are separated according to predetermined amounts, a plug being threadedly engaged into the rear end of said conductive tubular member, constituting the closed end thereof. 100
5. A thermostat for an automatic dish washing and drying machine or the like, comprising a tubular body with a reduced front end and opened at the rear end for mounting upon a water or the like pipe lines in a manner so that the fluid may enter, a conductive tubular member with a closed rear end and mounted at the front through said reduced end and extending towards the rear of said tubular body so as to be surrounded by said fluid, a bimetal strip and a plain strip parallel to each other and extending through said conductive tubular member and supported at the rear ends upon the closed rear end of said conductive tubular member, a contact mounted on an insulated terminal mounted on the free end of each of said strips for connection in an electric circuit to control the circuit according to certain temperature effects upon the bimetal strip, a finger attached upon the free end of said plain strip, and a cam rotatively supported in a manner so that its periphery acts against the finger to hold away the plain strip flexed so that the said terminals are separated according to predetermined amounts, the front end of said tubular body being formed with a flange, and a casing being mounted upon said flange and covering said cam and finger and all parts to the rear, an operating knob being disposed outside of said casing and mounted upon a stem extended into the casing and connected with said cam whereby the cam may be adjusted to control the position of said finger, a cable casing being attached upon said casing to constitute housing for the passage of leads to connect with said terminals. 110
- 95 105 110 115 120 125 130 135 140 145 150

6. A thermostat for an automatic dish washing and drying machine or the like, comprising a tubular body with a reduced front end and opened at the rear end for mounting upon a water or the like pipe line in a manner so that the fluid may enter, a conductive tubular member with a closed rear end and mounted at the front through said reduced end and extending towards the rear of said tubular body so as to be surrounded by said fluid, a bimetal strip and a plain strip parallel to each other and extending through said conductive tubular member and supported at the rear ends upon the closed rear end of said conductive tubular member, a contact mounted on an insulated terminal mounted on the free end of each of said strips for connection in an electric circuit to control the circuit according to certain temperature effects upon the bimetal strip, a finger attached upon the free end of said plain strip, and a cam rotatively supported in a manner so that its periphery acts against the finger to hold away the plain strip flexed so that the said terminals are separated according to predetermined amounts, said cam comprising a core portion, a peripheral portion with a rod radially slidable in said core portion so that the peripheral portion may be adjusted, resilient means urging said peripheral portion inwards, and means for holding the peripheral portion extended when desired to a predetermined amount, a stem being connected with said core portion and extending outwards and carrying a knob whereby the core portion may be rotated. 80
- 10 15 20 25 30 35 40 45 50 55 60 65 70 75 80 85 90 95 100 105 110 115 120 125 130 135 140 145 150
7. A thermostat for an automatic dish washing and drying machine or the like, comprising a tubular body with a reduced front end and opened at the rear end for mounting upon a water or the like pipe line in a manner so that the fluid may enter, a conductive tubular member with a closed rear end and mounted at the front through said reduced ends and extending towards the rear of said tubular body so as to be surrounded by said fluid, a bimetal strip and a plain strip parallel to each other and extending through said conductive tubular member and supported at the rear ends upon the closed rear end of said conductive tubular member, a contact mounted on an insulated terminal mounted on the free end of each of said strips for connection in an electric circuit to control the circuit according to certain temperature effects upon the bimetal strip, a finger attached upon the free end of said plain strip, and a cam rotatively supported in a manner so that its periphery acts against the finger to hold away the plain strip flexed so that the said terminals are separated according to predetermined amounts, said cam comprising a core portion, a peripheral portion with a rod radially slidable in said core portion so that the peripheral portion may be adjusted, resilient means urging said peripheral portion inwards, and means for holding the peripheral portion extended when desired to a predetermined amount, a stem being connected with said core portion and extending outwards and carrying a knob whereby the core portion may be rotated, and a tube being mounted upon said stem and connected with an arm adapted to hold said peripheral portion extended and constituting the means for holding said portion extended. 110
- 115 120 125 130 135 140 145 150
8. A thermostat for an automatic dish washing and drying machine or the like, comprising a tubular body with a reduced front end and opened at the rear end for mounting upon a water or the like pipe line in a manner so that the fluid may enter, a conductive tubular member with a closed rear end and mounted at the front through said reduced end and extending towards the rear of said tubular body so as to be surrounded by said fluid, a bimetal strip and a plain strip parallel to each other and extending through said conductive tubular member and supported at the rear ends upon the closed rear end of said conductive tubu- 150

15 member, a contact mounted on an insulated terminal mounted on the free end of each of said strips for connection in an electric circuit to control the circuit according to certain temperature effects upon the bimetal strip, a finger attached upon the free end of said plain strip, and a cam rotatively supported in a manner so that its periphery acts against the finger to hold away the plain strip flexed so that the said terminals are separated according to predetermined amounts, said cam comprising a core portion, a peripheral portion with a rod radially slidable in said core portion so that the peripheral portion may be adjusted, resilient means urging said peripheral

portion inwards, and means for holding the peripheral portion extended when desired to a predetermined amount, a stem being connected with said core portion and extending outwards and carrying a knob whereby the core portion may be rotated, and a tube being mounted upon said stem and connected with an arm adapted to hold said peripheral portion extended and constituting the means for holding said portion extended, a finger being attached upon the outer end of said tube and adjustable relative to said knob to control the moving of the peripheral portion from the retracted to the extended positions.
